UNITED STATES PATENT OFFICE.

EDWIN E. SLICK, OF JOHNSTOWN, PENNSYLVANIA.

RAIL ANCHOR.

1,417,473.

Specification of Letters Patent. Patented May 23, 1922.

Application filed August 9, 1919. Serial No. 316,380.

To all whom it may concern:

Be it known that I, EDWIN E. SLICK, citizen of the United States, and a resident of Johnstown, in the county of Cambria and 5 State of Pennsylvania, have invented a new and useful Improvement in Rail Anchors, of which the following is a full, clear, and exact description.

The present invention relates broadly to 10 rail anchors, and more particularly to an anchor of this character adapted to prevent longitudinal creeping of the rails.

In the operation of railways, and particularly those in which the excess of travel is 15 in one direction, it has been found that the rails, crossing switches, and the like, are thrown out of alignment, due to the creeping of the rails or the tendency of the same to follow the train.

20 The principal object of the present invention is to provide an anticreeping device for rails which is easily applied and which, while permitting a limited movement of the rail in one direction, automatically clamps 25 the rail upon any tendency thereof to move in the opposite direction.

The foregoing and other objects, together with their attendant advantages, will be apparent as the invention becomes better understood by reference to the accompanying specification and drawings forming a part thereof, it being premised that changes may be made in the various details and the manner of operation within the scope of the 35 appended claims, without departing from the spirit of my invention.

Figure 1 is a top plan of a section of a railway having my invention applied thereto;

40 Figure 2 is a cross sectional view on the line II—II of Figure 1;

Figure 3 is a side view of the section of railway illustrated in Figure 1; and

45 Figure 4 is an enlarged detail view of the rail-gripping member.

Referring more particularly to the drawings, I have illustrated a portion of a usual tie 2 for supporting the rail 4. My improved rail anchor for preventing longitudinal creeping of the rail with respect to the ties preferably comprises a bar 5, having its opposite ends 6 extending in substantially horizontal planes, and its intermediate portion 7 formed to extend in a vertical 50 plane to abut against one side of the tie. One of the ends of the bar is provided with

a hook 8, adapted to receive a portion of the base flange of the rail 4. On the opposite side of the bar 5 is pivotally riveted a member 9 for gripping the base flange of the 60 rail. This gripping member 9 has two cam faces formed thereon, one being a vertical eccentric cam face 10 for engaging the side of the base flange and the other a downwardly inclined cam face 11 for engaging 65 the top of the base flange at the edge thereof.

When the rail anchor is applied the gripping member 9 is swung to a position substantially at right angles to that illustrated 70 in the drawing, whereupon the bar 5 may be adjusted on the rail in abutting relation to the tie 2. The gripping member 9 is then swung into gripping engagement with the base flange of the rail. The gripping member 75 9 is longitudinally acting, that is to say, the longitudinal creeping tendency of the rail is resisted by the flange gripping member 9 and the gripping action increases in proportion to the longitudinal creeping 80 tendency of the rail. Any tendency of the rail to creep in the direction of the arrow A, as shown in Figure 1, will be effectively prevented by the rail anchoring device.

The bar 5 and the flange gripping device 85 9 are preferably riveted together as illustrated, thus giving a strong and positive connection without screw-threaded nuts or other parts which would be liable to work loose.

90 While I have specifically illustrated and described the preferred embodiment of my invention, it is to be understood that the invention is not limited to its illustrated embodiment, but may be embodied in other 95 structures within the scope of the following claims.

I claim:

1. An anticreeping device for rails, comprising a bar having a portion adapted to 100 abut against one side of a tie, and having provision at one end for engaging one side of the base flange of the rail, and a horizontally swinging member on the opposite end of said bar having wedging faces effective on different portions of the base flange 105 of the rail at substantially right angles, substantially as described.

2. An anticreeping device for rails, comprising a bar having its intermediate portion extending in a substantially vertical 110 plane to abut against one side of a tie and

its end portions extending in substantially horizontal planes, means on one end of the bar for engaging the base flange of the rail, and a horizontally swinging gripping member on the opposite end of the bar, said gripping member having an eccentric face adapted to engage the side of the base flange of the rail, and a second eccentric face inclined to act as a wedge and adapted to engage the top of said flange, substantially as described.

3. An anticreeping device for rails, comprising a bar having means on one end for engaging one side of the base flange of the rail, and a horizontally swinging gripping member on the opposite end of the bar for engaging the other side of the base flange of the rail, an intermediate portion of said bar being bent to extend in a vertical direction to form a tie-abutting portion effective throughout the major portion of the length of the bar, substantially as described.

4. An anticreeping device for rails, comprising a bar having means on one end for engaging one side of the base flange of the rail, and a horizontally swinging gripping member riveted on the opposite end of the bar for engaging the other side of the base flange of the rail, said bar having an inter-

mediate portion bent to extend in a vertical direction to form a tie-abutting portion effective throughout the major portion of the length of the bar, substantially as described.

5. In an anticreeping device for rails, a bar having means on one end for engaging one side of the base flange of the rail, and a horizontally swinging gripping member on the opposite end of the bar adapted to overlie and engage the other side of the base flange of the rail, said bar having an intermediate portion bent to extend in a vertical direction to form a tie-abutting portion, substantially as described.

6. An anticreeping device for rails, comprising a bar having its intermediate portion extending in a vertical plane to abut against one side of a tie, means on one end of the bar for engaging one side of the base flange of a rail, and a horizontally swinging gripping member permanently secured to the opposite end of said bar for engaging the other side of the base flange of the rail, substantially as described.

In testimony whereof, I have hereunto set my hand.

EDWIN E. SLICK.
